UNITED STATES PATENT OFFICE

2,042,126

ELECTRIC INCANDESCENT LAMP

Henry Forbes Russell, Quincy, Mass.

Application December 11, 1933, Serial No. 701,768

3 Claims. (Cl. 176—26).

My invention relates to electric incandescent lamps which comprise electric energy translating electrodes and filaments which are heated to incandescence during operation and which are enclosed in a hermetically sealed transparent glass bulb or other container. This invention comprises a system of moveable and interchangeable elements of construction within the sealed bulb. My major object is to provide a system whereby reserve concentrated filaments may be protected from the great evaporating power of a highly energized and intensely heated and concentrated filament, and in which, upon failure of the original heated filament, the said reserve filaments may move from a relatively remote position to a pre-determined position or to a central position in the said sealed container, and in which a reserve filament when in the said central position may be individually energized.

A further object of this invention is to provide exceedingly simple, effective and practical means to actuate my system.

My invention finds particular application to lamps of the higher wattage type which are quite expensive and of comparatively short life, a condition which has seriously hampered their commercial use. Furthermore, the operating temperature of filaments of comparatively lower wattage lamps have been lower than they could be, more on the account of the commercial demand for a long life lamp than the lack of knowledge of how to keep the temperature up. My system therefore provides means for a lamp of longer life, or greater efficiency in lumens per watt consumed, or a combination of both said features.

I attain these objects by means of mechanism illustrated in the accompanying drawing, in which:—

Figure 1 is a vertical partial section of my electric incandescent lamp, and in which figure is shown a tubular glass stem 2 having an annular flange 23 at its lower extremity, leading-in wires 3 individually sealed into the press 24 of the said stem, and a concentrated tungsten filament 4 bridging the said leading-in wires. Furthermore is shown a transparent glass bulb 1 having a tubular neck 20 continuous therewith and adapted to admit the stem 2 with its annular flange 23. An exhaust tube 17 is sealed to the said stem so that one end thereof opens into the interior of the bulb when the stem is sealed thereto. The other end of the said exhaust tube remains open until after the bulb is sealed to the

stem at 19 and the lamp is exhausted and filled with the usual filling of nitrogen and argon gases after which it is sealed off at 18.

In Fig. 1 is shown a non-conducting, rotating 8 gram glass wheel 5 mounted on a fixed tungsten axle 6; all of which and more following shall be shown in full detail and described in full detail later.

Multiple tungsten conducting arms 7, 7, 7 imbedded in the said wheel, extend radially and outwardly, and carry multiple bridging concentrated tungsten filaments 4, 4, 4 respectively. The said multiple conducting arms and their said respective bridging filaments move and rotate with the said wheel and are interchangeable and are capable of being individually energized, as will be shown.

Multiple tungsten semi-circular contacts 8 have multiple downwardly projecting and supporting tungsten arms 8a respectively; said supporting arms being unmoveably mounted, without touching each other. The said semi-circular contacts 8 are in fixed relation with the said leading-in wires 3, respectively.

A 19 gram tungsten weight 10 is inserted in fixed relation at an off-centered point in the said wheel, and has for its object to produce greater momentum in one side of the wheel when the wheel is given motion.

In regard to the manner in which this invention is to be used: A substantial shake or series of shakes, not sufficient to rupture any portion of my lamp, and parallel to the plane of the wheel 5, and in a direction in this said plane as will give motion to and control motion of the said weight 10 relative to the lamp container, shall be applied externally to my entire lamp; whereupon abrupt cessation of the motion of the lamp container shall cause, by momentum of the weight, the said wheel with its multiple conducting arms 7, 7, 7 and their respective filaments 4, 4, 4 to move, rotate and inter-change from one position to another in the sealed container. Furthermore, by these means the said conducting arms with their respective filaments move, rotate and inter-change, one after another, from a relatively remote position to a central position in the said container.

When any two adjacent associated conducting arms such as 7 with their bridging concentrated filament 4 enter the central position in the container, as shown, they contact the multiple semi-circular contacts 8 respectively, and the said arms with their said filament individually enter electrical circuit.

According to my invention, it becomes exceedingly important to protect the reserve filaments from the energized filament and to get the reserve filaments into a central position in the container, otherwise the concentrated filaments in operation would melt the container, and if a larger container were provided, the cost of such a container, and of exhausting and re-filling, and of packaging, storing and shipping, along with the un-adaptability to many standard installing fixtures would make such a lamp undesirable.

According to my invention, I am concerned to state that the wheel must not be equally balanced, otherwise no amount of shaking of the lamp can make the wheel move relative to the lamp container.

I will now show in full detail and describe in full detail the construction and combinations of my invention and the manner in which the same is to be made and used.

Figures 2 and 3 are detail figures of part of the filament carrier, and in which figures respectively is shown a recess 11 to receive and hold in fixed relation the tungsten weight shown in perspective in Fig. 4. An axle hole 12 is adapted to receive the tungsten axle shown in perspective in Fig. 5. The ends 1a of three sets of associated conducting arms of the said 30 multiple conducting arms are shown imbedded in and supported in fixed radially and outwardly projecting direction in the said wheel.

Fig. 5 is a perspective view of the tungsten axle, and in which figure is shown a flanged face 6a for the purpose of keeping the said wheel in position, and is shown an end 6b to be imbedded in and supported in fixed relation in some stable portion of the lamp, preferably the upper part of the stem 2' of Fig. 1.

Fig. 6 is a perspective view of one of the multiple tungsten conducting arms, and in which figure is shown an outermost end 7b to support one end of one of the multiple concentrated filaments, and is shown an innermost end 7a to be fixed in the wheel as has been described.

Fig. 7 is a side elevation, when horizontally placed, of the contacting mechanism, and in which figure is shown the non-conducting, rotating wheel 5, mounted upon its fixed axle 6, said axle 6 being imbedded in and finding support in the stem 2'. Furthermore is shown two associated conducting arms 7, 7 with the associated concentrated filament 4, contacting the semi-circular contacts 8, 8 in brushing contact respectively. Furthermore is shown the semi-circular contacts 8, 8 with their downwardly projecting and supporting arms 8a, 8a respectively; said arms being imbedded in and finding support, without touching each other, in the stem 2'. Furthermore is shown the leading-in wires 3, 3 in fixed relation with the semi-circular contacts 8, 8 respectively.

I intend that, referring to Fig. 1, the force of friction of the wheel 5 upon its axle 6, shall at all times exceed the force of gravity upon the weight 10, whereby the entire mechanism remains motionless regardless of the position in which my lamp is held. I intend that the said force of friction shall be as small as possible consistent with the force necessary to counteract motion of the wheel by gravity.

It can be seen that the same controlled motion of the rotating wheel might be obtained in an other fashion, as for example magnetically, having weight 10 of magnetic material in a con-

veniently applied magnetic field; or again by making use of a coiled spring suitably controlled. Such methods might be applicable to very large lamps which do not adapt themselves to being shaken, or to lamps which are not easily reached. Again, it can be seen that my reserve filaments may be stopped accurately and positively in operative position by simple means such as a ratchet, or stop-arm, or any other type of convenient brake. I therefore do not wish to limit myself to a shaking method for the purpose of actuating my system or controlling the motion of my system, although it is apparent that a shaking method is a most excellent and preferable way of actuating and a satisfactory way of controlling the motion of my system.

I have found at present that I may be limited to only two reserve filaments and possibly to one reserve filament, not because of any mechanical difficulty in putting many reserve filaments into the sealed bulb, but because the intensely heated glow-space of the energized concentrated filament demands a large isolated space for itself, furthermore any reserve filaments within this said demanded space become either burned out or heavily coated with a tungsten deposit coming from electron emission of the energized filament, and, the said tungsten deposit, being a conductor of electricity, changes, in an uncontrollable fashion, the resistance of such reserve filaments; both results thereby rendering such reserve filaments exceedingly unreliable.

During the operation of my lamp, the energized filament in the central position of the sealed container gives off large quantities of electron emissions. Thus a thickness of tungsten deposit varying from 0 to $\frac{1}{16}$ inch in thickness will deposit on the inner wall of the sealed container. This extreme thickness of deposit on a 1000 watt reserve filament would reduce the resistance of this filament approximately 68%. My system largely overcomes the difficulty of the deposition of tungsten on the reserve filaments by having the reserve filaments out of the path of the major portion of the moving electron emissions.

Again, when one of my reserve filaments burns out, it usually becomes greatly distorted and bent out of shape as a result of the great heat which has been evolved. The difficulty heretofore usually experienced in the short-circuiting and fusion of the burnt-out filament with the adjacent reserve filaments is entirely overcome in my system by having the reserve filaments far out of reach of the burnt-out filament.

According to my invention, the lamp is removed from its operating position after the first filament in the central position of the sealed container is rendered useless. The lamp is shaken in the direction in which it is desired to make the associated electrodes and filaments move; which direction may be clock-wise or counter-clock-wise. By the energy of the momentum in the weight, the wheel and associated electrodes and filaments continue in their motion after the lamp container is abruptly stopped, and rotate until the associated electrodes and filaments next in turn enter the central operating position. This it will do with ease, one shake usually being sufficient to actuate this entire motion. The lamp is now put back in operative position and is again ready for use. Upon the burning-out of this latter filament, the next filament, in like manner, is rotated into operative position.

Obviously I do not wish to be limited to the exact details of construction as herein described.

as these may be varied within the limits of the appended claims without departing from the conception of my invention.

What I claim as new and desire to secure by Letters Patent of the United States, is:

1. In an electric incandescent lamp, the combination of a hermetically sealed transparent container, a press in said container, lead wires supported by said press, and a plurality of associated electrodes, and filaments mounted on a rotatable member the rotatable member having its center nearer the press than the center of the container, therein, said member being supported at the top of said press, substantially as herein described.

2. In an electric incandescent lamp, the combination of a hermetically sealed transparent container, a press in said container, lead wires supported by said press, and a plurality of as-

ociated electrodes, and filaments mounted on a rotatable member the rotatable member having greater weight on one side of its pivotal point than on the other side of its pivotal point and having its center nearer the press than the center of the container, therein, said member being supported at the top of said press, substantially as herein described.

3. In an electric incandescent lamp, the combination of a hermetically sealed transparent container, a press in said container, lead wires supported by said press, and a plurality of associated electrodes and filaments mounted on a rotatable member the rotatable member having greater weight on one side of its pivotal point than on the other side of its pivotal point, therein, said member being supported at the top of said press, substantially as herein described.

HENRY FORBES RUSSELL.
